UNITED STATES PATENT OFFICE.

CHARLES N. TEETER, OF HAGERSTOWN, INDIANA.

SPLASH LUBRICATION SYSTEM.

946,923.

Specification of Letters Patent. Patented Jan. 18, 1910.

Application filed March 17, 1909. Serial No. 483,912.

To all whom it may concern:

Be it known that I, CHARLES N. TEETER, a citizen of the United States, residing at Hagerstown, in the county of Wayne and State of Indiana, have invented certain new and useful Improvements in Splash Lubrication Systems; and I do hereby declare the following to be a full, clear, and exact description of the invention, such as will enable others skilled in the art to which it appertains to make and use the same.

My invention relates to splash lubrication systems for hydrocarbon engines.

It has for its object to regulate to better advantage the amount of oil through which the crank of the engine passes at each revolution.

The invention comprises an inner receptacle or pan arranged within the under bonnet of the crank case in position to receive the crank on its down stroke, and means for regulating the flow of the lubricating fluid to said pan from said under bonnet proper into which it is splashed from the pan by the action of the crank.

The invention also consists in the features of construction and combinations of parts hereinafter described and specified in the claims.

30 In the accompanying drawing illustrating the preferred embodiments of my invention: Figure 1 is a broken side elevation of the under bonnet of the crank case of a four cylinder engine, the crank shaft and one of the cranks being shown. Fig. 2 is a cross section on the line $x-x$ of Fig 1, and Fig. 3 is an enlarged broken section on the line $y-y$ of Fig. 1, the crank and shaft being omitted.

40 While I have illustrated my invention as applied to the crank case of a four cylinder engine, it will be understood that it may be employed with equal success in connection with the crank cases of engines having one or any number of cylinders and cranks.

45 In the drawing, 1 designates the under bonnet of the crank case which is divided into four compartments by the ribs 2 preferably placed equi-distant apart and extending to a suitable height from the bottom. The portion of said bonnet extending between two adjacent ribs may be termed the under bonnet proper of one of the cranks 3 on the shaft 4. A funnel-shaped groove 5 is formed at the bottom of each of the compartments and leads to a discharge nozzle 6

preferably closed by a screw plug 7, whereby the lubricating fluid may be drawn off. An inner pan 8 is arranged centrally of each compartment and is in position to be entered by the crank on its down stroke. Said pan preferably conforms to the path of movement of the crank as illustrated in Figs. 2 and 3, and is only slightly wider than the crank, as shown in Fig. 1. The inner pan is preferably supported above the bottom of the crank case and is rigidly held in place upon upwardly projecting lugs 9 and forms a bridge over the funnel-shaped groove or trough 5.

70 In order to permit the lubricating fluid in the under bonnet proper to pass into the inner pan, the sides of which extend up to about the level of the tops of the ribs 2, an opening 10 is formed preferably in the bottom of said pan. A needle valve 11 is fitted in said opening and is adjustable by means of a thumb nut 12 on its screw-threaded stem 13 which extends through the bottom of the under bonnet, as shown in Figs. 1 and 3. A stuffing box 14 is located in the bottom of said bonnet to prevent the oil from flowing out along the valve stem.

75 It will be noted that before the engine is started, the oil will seek its level in the pan but that when the crank begins to turn and passes through said pan, it will splash the oil from it into the outer compartment. The oil must then find its way back into the pan through the opening 10. The flow of oil through this opening may be regulated to suit requirements by means of the needle valve.

I claim:

1. In a splash lubrication system, the combination, with the under bonnet of the crank case, of a pan arranged therein in position to be entered by the crank on the down stroke thereof, said pan having an opening to permit the lubricating fluid to enter said pan from said bonnet.

2. In a splash lubrication system, the combination, with the under bonnet of the crank case, of a pan arranged therein above the bottom of the bonnet in position to be entered by the crank on the down stroke thereof, said pan having an opening to permit the lubricating fluid to enter said pan from said bonnet.

3. In a splash lubrication system, the combination, with the under bonnet of a crank case, of a pan arranged therein in

position to be entered by the crank on the down stroke thereof, said pan being shaped to conform to the path of movement of the crank and having an opening to permit the lubricating fluid to enter said pan from said bonnet.

4. In a splash lubrication system, the combination, with the under bonnet of the crank case, of a pan arranged therein above 10 the bottom of the bonnet in position to be entered by the crank on the down stroke thereof, said pan being shaped to conform to the path of movement of the crank and having an opening to permit the lubricating 15 fluid to enter said pan from said bonnet.

5. In a splash lubrication system, the combination, with the under bonnet of a crank case, of a pan arranged therein in position to be entered by the crank on the 20 down stroke thereof, said pan having an opening in its bottom to permit the lubricating fluid to enter said pan from said bonnet.

6. In a splash lubrication system, the combination, with the under bonnet of the crank case, of a pan arranged therein in position to be entered by the crank on the 25 down stroke thereof, said pan having an

opening to permit the lubricating fluids to enter said pan from said bonnet, and means 30 to regulate the flow through said opening.

7. In a splash lubrication system, the combination, with the under bonnet of the crank case, of a pan arranged therein in position to be entered by the crank on the 35 down stroke thereof, said pan having an opening to permit the lubricating fluid to enter said pan from said bonnet, and an adjustable valve in said opening for regulating the flow through it.

8. In a splash lubrication system, the combination, with the under bonnet of the crank case, of a pan arranged therein in position to be entered by the crank on the down stroke thereof, said pan having an 45 opening to permit the lubricating fluid to enter said pan from said bonnet, the bottom of said bonnet being provided with a funnel-shaped trough leading to a discharge nozzle.

In testimony whereof, I affix my signature, in presence of two witnesses.

CHARLES N. TEETER
